UNITED STATES PATENT OFFICE.

ORLANDO GARRISON, OF DAYTON, OHIO.

GRINDING-MACHINE.

1,328,953.

Specification of Letters Patent. Patented Jan. 27, 1920.

Application filed June 4, 1917. Serial No. 172,717.

To all whom it may concern:

Be it known that I, ORLANDO GARRISON, citizen of the United States, residing at Dayton, in the county of Montgomery and State 5 of Ohio, have invented certain new and useful Improvements in Grinding-Machines, of which the following is a specification.

My invention relates to metal grinders and more particularly to internal grinding 10 means for surfacing or finishing and polishing the interior faces of openings or recesses in metallic or other bodies but which may be employed for external operations, surface grinding, milling or other analogous operations.

The object of the invention is to simplify the structure as well as the means and mode 20 of operation of such machines, whereby they will not only be cheapened in construction but will be efficient in use, positive in operation, accurate in action, easily and quickly 30 adjusted, and unlikely to get out of repair.

A further object of the invention is to provide an abrasive or cutting member together with supporting and driving connections therefor which will enable such abrasive or cutting member to be operated within restricted openings or spaces.

A further object of the invention is to provide improved means for supporting and 35 operatively connecting the driving element of the cutter or grinder within a space substantially limited to the width or thickness of the driving element and to further provide improved lubricating means.

A further object of the invention is to provide improved adjustable supporting means for the work whereby the work may be successively presented in different angular 40 positions with nice accuracy of adjustment.

A further object of the invention is to provide improved setting means for initially adjusting the work in relation with the 45 grinder or cutter which will predetermine and control the successive positions to which the work is subsequently adjusted.

With the above primary and other incidental objects in view as will more fully appear in the specification, the invention consists of the features of construction, the parts and combinations thereof, or their equivalents, as hereinafter described and set forth in the claims.

Referring to the drawings, Figure 1 is a

side elevation partly broken away of the assembled machine. Fig. 2 is a front elevation of the upper portion thereof. Fig. 3 is a transverse sectional view looking upward of the main frame or pedestal, showing in bottom plan view the work supporting and adjusting element. Fig. 4 is a vertical sectional view of the work supporting apparatus. Fig. 5 is a top plan view of the work supporting head or chuck, showing the work positioned therein and the relative position of the grinder wheel or cutter.

Like parts are indicated by similar characters of reference throughout the several views.

Referring to the drawings, 1 is the upright main frame or pedestal having upon its forward face vertically disposed ways or guides 2. Mounted to reciprocate vertically upon said guides or ways is a work supporting table 3. This table is elevated and lowered by means of a hand operated lever 4 connected to an oscillatory gear sector 5 which in turn meshes with a gear pinion 6 upon a transverse shaft 7 journaled in the main frame or pedestal 1. The shaft 7 carries a grooved sheave or pulley wheel 8 about which extends a short length of flexible cable 9. The cable 9 is positively engaged with the sheave or pulley by being looped or passed first inwardly and then outwardly through spaced holes in the rim of the sheave or pulley as indicated at 10. The opposite ends of the cable 9 are fixedly connected to the reciprocating work supporting table 3 at 11 and 12. The arrangement is such that as the pulley or sheave 8 is oscillated by means of the operating lever 4, the work supporting table 3 will be elevated or lowered upon the ways or guides 2. To facilitate the movement of the table 3 and hold it in adjusted position, there is provided a counter balance weight 13 suspended upon a cable 14 which passes around the sheave or pulley 8 and is attached thereto at the point 15. Located upon the front of the pedestal 1 above the vertical guides or ways 2 are transverse guides or ways 16 upon which is mounted a sliding head 17. This head 17 is moved to and fro by a feed screw 18 operable by a knurled head 19. Adjacent to the head 19 is a graduated scale 20 upon which the lateral variation of the head 17 upon each partial rotation of the feed screw, will be indicated. Journaled for os-

100
105
110

illatory movement in a suitable bracket or arm 21 projecting from the head 17 is a pendent arm 22. While the arm 22 is capable of movement to different radial positions it is normally held in a predetermined position by clamping bolts 23. This arm 22 carries at its lower end a grinding wheel, milling cutter or other operative element. Inasmuch as the device is particularly designed for use in restricted openings or spaces, the mounting and driving connections of the grinder or cutter must necessarily be compactly arranged. A transverse shaft is mounted in the bushings so supported in the extremity of the arm 22, and carries at its extremity outside said arm an operative element such as a grinding wheel 38, a cutter or other rotary tool. This shaft and the operative element carried thereby is driven by means of a pulley 34, secured upon said shaft within the eye 24 of the arm 22. The particular method of mounting the shaft in the arm 22 forms no part of the present invention and hence is not shown nor described in detail herein.

The pulley 34 is driven by a belt 40 from a drive pulley 41 mounted upon a transverse shaft 42 at the top of the machine. The belt 40 is guided intermediate idlers 43 in a parallel path of travel within the transverse limits of the grinding wheel or cutter 38 whereby the belt will not interfere with the work in inserting the grinding wheel or cutter and the arm 22 by which it is carried within the opening or recess in the work. For the purpose of adjusting or tightening the belt 40 the shaft 42 is mounted in an eccentric sleeve 44 rotatably carried in a bearing box 45 attached to a projecting head 46 at the top of the pedestal 1. The shaft 42 is rotated to drive the grinding wheel or cutter 38 by means of a belt driven pulley 47 carried upon the end thereof opposite the pulley 41. It will be understood that by adjusting the head 17 transversely which within limited distance is permitted by the flexibility of the drive belt 40, and by oscillating the arm 22 in a direction perpendicular to the direction of movement of the head 17, the grinding wheel or cutter may be accurately adjusted, either to compensate for wear or for variations in the finished product. These adjustments also facilitate the assemblage and the initial adjustment of the apparatus. Mounted upon the work supporting table 3 is a chuck for the work, comprising two concentric telescoped work supporting members. The outermost member comprises a circular recessed head 48 and a pendent integral sleeve 49. This outermost chuck member is revolubly mounted in the work supporting table 3 and rests upon a ball or antifriction thrust bearing 50. At its lower end the sleeve 49 of the outer chuck mem-

ber is screw threaded to receive a retaining collar 51. Intermediate the collar 51 and the under side of the table 3 is interposed a washer or collar 52 having a spline or pin 53 engaging in a longitudinal groove 70 54 in the screw threaded portion of the sleeve 49. The washer or collar 52 is preferably of hardened steel, bronze or other similar material which will afford a suitable bearing surface. The outer chuck member is thus easily revoluble in the work supporting table 3 and is retained in engagement therewith by the screw collar 51. The interior of the circular head 48 of the outer chuck member is preferably slightly 75 tapered as at 55 and the outer periphery of the head of the inner chuck member 56 is correspondingly tapered to engage the tapered face of the first mentioned chuck member. The inner chuck member is provided with a pendent sleeve 57 extending through the sleeve 49 of the outer chuck member and having a screw threaded extremity 58 projecting therebeyond. Engaging the screw threaded projecting end 58 80 of the sleeve 57 is a clamping collar 59 screw threaded upon the extension 58 and adapted to bear against the end of the sleeve 49. For convenience in tightening this collar it has been provided with radial 85 arms or handles 60. As the collar 59 is tightened against the end of the sleeve 49 it tends to draw the inner chuck member downward, insuring a non-yielding frictional engagement between the tapered surfaces 55. The chuck members are thus immovably engaged one with the other. To further this engagement they may be provided with an interconnecting dowel 61. Immediately above the screw threaded collar 59 is a split ring 62 surrounding the lower end of the exterior chuck member and adapted to be contracted thereupon by an eccentric or cam lever 63. This cam lever 63 is mounted in the end of a bolt or 95 stud 64 which extends through terminal ears 65 of the split ring 62 and which carries at its opposite end adjusting nuts 66. These nuts 66 may be adjusted to compensate for wear and to insure perfect contact 100 between the parts when the cam lever 63 is operated to the tightening position. In addition to the ears or lugs 65 between which the ring is split, the said ring 62 also carries two spaced ears or lugs 67 and 67' 105 through which are screw threaded oppositely disposed adjusting screws 68 and 68'. It will be understood that the split ring or clamping ring 62 is normally loose upon the sleeve 49 of the chuck member permitting 110 said chuck sleeve and split ring to be rotated independently. Loosely mounted for rotary movement about the sleeve 49 immediately above the split or clamping ring 62 is an index plate 69 from which projects 115

120

125

130

downward a stud or ear 70 in a position intermediate the adjacent ends of the adjusting screws 68 and 68' carried in the ears 67 and 67' of the split collar. The 5 split or clamping ring 62 and the index plate 69 are thus interengaged one with the other, but are capable of independent relative movement by loosening one of the adjusting screws 68 or 68' and tightening the other. Thus it will be seen that by loosening the screw 68 and tightening the screw 68' causing it to bear more heavily upon the pin or ear 70, said pin or ear will be pressed toward the right in Figs. 1 and 3 10 carrying with it the index plate 69. However, in practice the converse of this is true. The index plate and pendent stud or ear 70 are held stationary by means hereinafter described and by the manipulation of the 15 adjusting screws 68 and 68' the split ring or clamping ring 62 and the chuck upon which it is contracted by the cam 63 will be moved revolvably in relation with the index plate by using the pendent stud or ear 20 70 of the index plate as an abutment against which the adjusting screw operates. The index plate 69 is provided in accurately spaced radial position with notches or gage shoulders 71. Pivoted at 72 to the work 25 supporting table 3 is a swinging detent or stop member movable into and out of the peripheral notches of the index plate, against which the stop shoulders 71 engage to locate the index plate and parts carried there- 30 with in predetermined relative positions. One side of the peripheral notch of the index plate is preferably somewhat inclined as shown particularly in Fig. 3 to coact with a similarly inclined face upon the swinging 35 stop or detent 73 thereby affording a camming action which will tend to draw the stop shoulder 71 of the index plate into perfect contact with the swinging stop 73. In the drawing there have been shown but four 40 peripheral notches and stop shoulders 71 spaced equally apart in 90 degree positions in relation one with another. It will be obvious, however, that any number of such peripheral notches or stop shoulders may be 45 employed in accordance with the character of the work and the relative positions of adjustment which the work is to assume. In the adaptation of the device to the finishing of parts or pieces involving faces un- 50 55 equally arranged, the index plate may be correspondingly notched or shouldered to afford unequally spaced stop shoulders to agree with the several operative positions of the work. Assuming that the work to be performed is the surfacing or finishing of the interior faces of a substantially rectangular opening in the center of a gear wheel, as indicated at 75 in Fig. 9, the gear wheel would be positioned within the interior 60 65 of the head 56 of the internal chuck member where it would be held in a concentric position by jaws or gage blocks 76 secured to the interior walls of the chuck head, which jaws or gage blocks are formed at their inner ends with a series of teeth 70 corresponding with the teeth of the gear to be operated upon. The swinging detent or stop finger 73 is assumed to be engaged in one of the peripheral notches of the index plate with the stop shoulder 71 in close engagement with the detent. The eccentric or cam lever 63 is released to disengage the split or clamping ring 62 from the revolvable sleeve 49 of the chuck. The chuck is now rotated by hand freely upon its anti-friction ball bearing 50 and within the supporting table 3 and also in relation with the index plate 69 and the clamping or split ring 62, until the face of the opening or recess in the gear 75 to be initially surfaced is substantially in alignment with the surfacing face of the grinder 38. Having been roughly adjusted or brought to the approximate adjusted position by the free rotation of the chuck, the eccentric or cam lever 63 is then operated to engage the sleeve 49 of the chuck and lock the chuck in its relation with the split ring 62 and the index plate 69 which is positively engaged with the said ring or collar 62 through the interconnection of the pendent lug or stud 70 and the adjusting screws 68 and 68'. In order to secure the final or micrometer adjustment of the surface to be finished in exact parallel relation with the operating 100 face of the grinder 38, the adjusting screws 68 and 68' are manipulated by loosening one and tightening the other, causing one or the other to bear upon the lug or stud 70 of the index plate as an abutment and thereby turn the collar 62 and the chuck sleeve to which it is clamped in relation with the index plate which as before stated is being fixedly held by the detent or stop 105 110 115 120 125 130 73 engaged in one of the peripheral notches thereof.

When the adjustment has been accurately made, the operating lever 4 is oscillated to elevate the work table and carry the positioned gear 75 upward with it thereby causing the arm 22 and the grinder 38 carried thereby to protrude within the central opening within said gear. The initial face having been surfaced the table 3 is lowered and the swinging stop detent 73 is withdrawn from the peripheral notch of the index plate, leaving the chuck free to rotate within the table 3. At such time the clamping ring has been positively engaged with the chuck sleeve by the tightening of the eccentric or cam lever 63 and the index plate 69 is positively engaged with the clamping collar 62 by the interengagement of the pendent stud or lug 70 intermediate the adjusting screws 68 and 68' which have previously been 130

42
 tightened upon said lug or stud 70 to prevent relative movement of the collar and index plate. Therefore the chuck, the clamping ring, and index plate will rotate 5 in unison when the swinging detent 73 has been withdrawn. The said parts are therefore located to bring the next succeeding peripheral notch of the index plate into alignment with the swinging stop or detent 10 73 which by its engagement therein will accurately position the second face to be surfaced in relation with the grinder 38, without the necessity of preliminary adjustments before described. Each succeeding face to 15 be operated upon is brought to operative position by rotating the chuck to bring the corresponding peripheral notch or stop shoulder 71 into engagement with the swinging detent or stop 73. Thus, after having 20 accurately positioned the chuck to present the initial surface in perfect alignment with the grinder or cutter 38, the succeeding positions for angularly arranged faces may be found by merely rotating the interconnected 25 parts to present different peripheral notches or stop shoulders 71 in engagement with the stop or detent 73.

While the apparatus has been shown in a form particularly designed for grinding interior surfaces of small openings, it is obvious that it may be employed for surfacing exterior faces equally as well. In such case, the hollow chuck head 56 may be replaced by a flat table or platen to which the work 30 35 may be attached in any suitable manner. Such work supporting table or platen being common in drill presses, milling machines, shapers and other machine tools need not be here illustrated. It is sufficient to say that 40 the interior chuck member comprising the head 56 and the sleeve 57 is readily removable by the disengagement of the screw threaded clamping collar 59 without the removal or disengagement of other parts 45 to permit the substitution of other interchangeable heads of different size or an interchange of positioning jaw 76 or the replacement of said chuck member by a solid or flat top table or platen as before mentioned. Many uses other than those hereinbefore mentioned will be found for the apparatus forming the subject matter hereof in factories employing present day high efficiency methods involving great accuracy 50 55 of fittings and parts. While the device is particularly adapted for internal grinding, it is not to be limited to this purpose, nor are grinding operations the only uses to which it may be placed. It will be obvious 60 that a milling cutter or any other rotary tool may be substituted for the grinding wheel 38.

From the above description it will be apparent that there is thus provided a device 65 of the character described, possessing the

particular features of advantage before enumerated as desirable but which obviously is susceptible of modification in its form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

Having thus described my invention, I claim:—

1. In a machine of the character described, an operating element and a work supporting table relatively movable in relation one with the other, a work engaging chuck revolubly mounted upon said table, a rotary index member adapted to be arrested in different positions of revoluble adjustment in relation with the table, said index member and said chuck being capable of independent rotation, and means for locking 90 the chuck and index member against independent rotation.

2. In a machine of the character described, an operating element and a work supporting table relatively movable in relation with one another, a work engaging chuck revolubly mounted upon said table, an index member, and an adjusting member, said chuck, index member and adjusting member being relatively adjustable, and means for locking said elements in relation 100 105 one with another.

3. In a machine of the character described, an operating element and a work supporting table relatively movable in relation with one another, a work engaging chuck revolubly mounted upon said table, an index member rotatable in relation with the table and normally fixed in relation with the chuck, means for engaging the index member in 110 115 fixed relation with the table in different positions of revoluble adjustment, and means for positively interengaging the chuck and index member for rotation in unison, and means for relatively moving the chuck while 120 the index member is held in fixed relation with the table.

4. In a machine of the character described, an operating element and a work supporting table relatively movable in relation with one another, a work engaging chuck revolubly mounted upon said table, an index member and an adjusting member independently movable in relation one with the other, one of said members being con- 125 130

nected with the chuck and the other with the table, and means for interengaging said members in fixed relation one with the other.

5. In a machine of the character described, 5 an operating element and a work supporting table relatively movable in relation one with the other, a work engaging chuck revolvably mounted upon said table, an index member and an adjusting member independently 10 movable in relation one with the other, an abutment carried by one of said members and a variable element carried by the other member and engaging the abutment whereby the variation of the variable element will effect 15 a relative movement of said index member and adjusting member, one of said members being engaged with the table and the other with the chuck.

6. In a machine of the character described, 20 an operating element and a work supporting table relatively movable in relation one with the other, a work engaging chuck revolvably mounted upon said table, an index member adapted to be engaged with the table in different 25 positions of adjustment, an adjusting member adapted to be engaged with the chuck, an abutment carried by one of said members, oppositely disposed adjusting screws carried by the other member intermediate 30 which the abutment projects, said adjusting member and with it the chuck being movable by the adjustment of said screws in relation with the interposed abutment.

7. In a machine of the character described, 35 a main frame, a tool supporting arm and a work supporting table movable in relation one with the other, an operating tool carried at the end of said arm, an adjustable supporting head for the projecting arm movable 40 independently of the table in a direction angular in relation to the first mentioned relative movement of the table and arm, and means for actuating the tool at the end of said arm.

45 8. In a machine of the character described, a work supporting table, a tool supporting arm, a tool carried thereby, an adjustable head upon which the arm is adjustably mounted, said table, head and arm being each capable of adjustment independent of 50 the other two members in a different plane, and means for actuating the tool carried by said arm in all positions of adjustment.

9. In a construction of the character described, 55 a support, an adjustable member to be held in different positions of adjustment in fixed relation with the support, an index member, means for engaging the index member in various predetermined positions of adjustment in relation with the support, a coupling member adjustably engageable with both the adjustable member and index member, the engagement with each of said members being independent 60 of the other member, said coupling mem-

ber positively connecting the adjustable member and index member for movement in unison.

10. In a construction of the character described, a support, a revolute member 70 mounted thereon, an index collar loosely journaled on the revolute member, means for engaging the index collar with the support, in different positions of revolute adjustment, a coupling collar loosely journaled 75 upon the revolute member, means for fixedly engaging the coupling collar with the revolute member, and adjustable means for fixedly engaging the coupling collar with the index collar. 80

11. In a construction of the character described, a support, an adjustable member mounted thereon to be adjusted to different relative positions, in relation with the support, and index member, and a coupling 85 member therefor each mounted for relatively adjustable movement in relation with the other members and support, means for engaging the index member with the support in different predetermined positions of 90 adjustment, means for fixedly engaging the coupling member with the adjustable member and means for fixedly engaging the coupling member with the index member, substantially as specified. 95

12. In a construction of the character described, a support, a member to be adjusted, an index member, and a coupling member, each of said members being relatively movable in relation with the others 100 and with the support, means for engaging the index member with the support in various positions of adjustment, a micrometer adjusting means for fixedly engaging the coupling member with the index member 105 and means for fixedly engaging the coupling member with the adjustable member in different positions of relative adjustment.

13. In a construction of the character described, a support, a member to be adjusted, an index member, and a coupling member, each of said members being relatively movable in relation with the others and with the support, means for engaging the index member with the support in various 110 positions of adjustment, means for fixedly engaging the index member with the coupling member in various positions of adjustment and means for engaging the coupling member with the member to be 115 adjusted in various positions of adjustment, substantially as specified.

14. In a construction of the character described, a support, a member to be adjusted, an index member, and a coupling member, each of said members being relatively movable in relation with the others and with the support, means for engaging the index member with the support in various 120 positions of adjustment, means for fixedly en- 125 gaged with the other member, said coupling mem-

gaging the member to be adjusted in relation with the index member by the medium of said coupling member and micrometer means for relatively varying the relation of the 5 member to be adjusted and the index means.

15. In a construction of the character described, a support, a member to be adjusted to various positions in relation with the support, an index member, means for 10 engaging the index member in various positions of adjustment in relation with the support, means for locking the adjustable member in various positions of adjustment in

relation with the index member, and means independent of said locking means for further adjusting the adjustable member in relation with the index member and for fixedly maintaining it in such further adjusted relation.

In testimony whereof I have hereunto set 20 my hand this 31st day of May, A. D. 1917.

ORLANDO GARRISON.
